(57) **CLAIM**

The ornamental design for a tool storage stool, as shown and described.

DESCRIPTION

FIG. 1 is a top perspective view with the lid slightly displaced of a tool storage stool showing my new design; FIG. 2 is a front side view with the lid slightly displaced thereof;

FIG. 3 is a back side view thereof;

FIG. 4 is a top side view thereof;

FIG. 5 is a bottom side view thereof;

FIG. 6 is a left side view with the lid slightly displaced thereof;

FIG. 7 is a right side view thereof;

FIG. 8 is an underside perspective view thereof;

FIG. 9 is a side sectional view taken along lines 9-9 from FIG. 3 thereof;

FIG. 10 is a side sectional view taken along lines 10-10 from FIG. 3 thereof.

FIG. 11 is a top perspective view with the lid slightly displaced for a tool storage stool showing a second embodiment thereof;

FIG. 12 is a front side view with the lid slightly displaced in the second embodiment thereof;

FIG. 13 is a back side view in the second embodiment thereof;

FIG. 14 is a top side view in the second embodiment thereof;

FIG. 15 is a bottom side view in the second embodiment thereof;

FIG. 16 is a left side view with the lid slightly displaced in the second embodiment thereof;

FIG. 17 is a right side view in the second embodiment thereof;

FIG. 18 is an underside perspective view in the second embodiment thereof;

FIG. 19 is a side sectional view taken along lines 19-19 from FIG. 13 in the second embodiment thereof; and,

(Continued)

FIG. 20 is a side sectional view taken along lines 20-20 from FIG. 13 in the second embodiment.
